CLAIM

We claim the ornamental design for a rotary power tool, as shown and described.

DESCRIPTION

FIG. 1 is a rear perspective view of a rotary power tool showing our new design;

FIG. 2 is a left side elevation view thereof;

FIG. 3 is a right side elevation view thereof;

FIG. 4 is a top plan view thereof;

FIG. 5 is a bottom plan view thereof; and

FIG. 6 is a front elevation view thereof; and,

FIG. 7 is a rear elevation view thereof.

The even broken lines in the drawings illustrate portions of the rotary power tool that forms no part of the claimed design. Additionally, the dash-dot broken lines in the drawings illustrate boundaries of the claimed design and form no part thereof.
